(57) **CLAIM**

We claim the ornamental design for a food plate, as shown and described.

DESCRIPTION

FIG. 1 is a top perspective view of a food plate.
 FIG. 2 is bottom perspective view of a food plate.
 FIG. 3 is a top view of a food plate.
 FIG. 4 is a bottom view of a food plate.
 FIG. 5 is an elevated front view of a food plate.
 FIG. 6 is an elevated rear view of a food plate.
 FIG. 7 is an elevated left side view of a food plate.
 FIG. 8 is an elevated right side view of a food plate; and,
 FIG. 9 is a cross sectional view of a food plate taken along line 9-9 in FIG. 3.

The broken lines in the figures represent unclaimed portions of the food plate. The dot-dash-dot broken line around the interior of the perimeter of the food plate and surrounding the claimed portion near the center of the food plate, illustrate the boundary of the claimed invention and form no part of the claimed design.
